PRINTING APPARATUS

Harry L. Latz, New York, N. Y., assignor to Harry Latz Service, Inc., New York, N. Y., a corporation of New York

Application July 2, 1937, Serial No. 151,574

20 Claims. (Cl. 101—57)

The invention relates to printing apparatus and has for its object to provide a novel apparatus whereby printed items may be readily added to previously printed matter to harmonize and accord therewith. The invention contemplates particularly the provision of a printing apparatus designed to function as a personal print machine for imparting to printed matter the appearance of having been specially prepared for the individuals receiving the same. Other more specific objects will appear from the description hereinafter and the features of novelty will be pointed out in the claims.

In the accompanying drawings which illustrate an example of the invention without defining its limits, Fig. 1 is a side elevation of the novel apparatus; Fig. 2 is an opposite side elevation partly in longitudinal section; Fig. 3 is a plan view with parts broken away; Fig. 4 is a vertical cross-section on the line 4—4 of Fig. 2; Fig. 5 is a fragmentary end elevation; Fig. 6 is a fragmentary detail section on the line 6—6 of Fig. 3; Fig. 7 is a detail section on the line 7—7 of Fig. 1; Fig. 8 is a fragmentary sectional elevation of the apparatus, and Fig. 9 is an enlarged detail view of a novel connection forming part of the apparatus.

In its illustrated form the machine is provided with a frame consisting of spaced, parallel upper side members 10 and a base-plate 11 extending between and connecting said side members 10, the latter in addition serving as supports for a horizontal bed-plate 12 located at a distance above the base-plate 16, as shown in Figs. 2, 4 and 5. The side members 10 of the frame are continued upwardly in the form of supports or arms 13 which project horizontally in spaced parallel relation over the bed-plate 12 and have their free ends connected by means of a transverse guide plate 14 removably secured in position in any suitable manner as by means of bolts 15.

As shown in Fig. 2, the guide plate 14 is designed to function as a vertical guide for an upper carrier 16 which at its lower end is provided with a stamping or pressure member 17 of any suitable type and fixed in place in any conventional way, the arrangement being such that said upper carrier 16 is vertically slidable relatively to said guide plate 14, as will appear more fully hereinafter. For the purpose of vertically reciprocating the upper carrier 16 and the stamping or pressure member 17, in the operation of the machine, said carrier is supported upon a head 18, preferably so as to be

vertically adjustable relatively thereto. The adjustment of the upper carrier 16 on the head 18 may be effected in any suitable manner, as for instance, by providing the carrier 21 with a lug 19 in which an adjusting screw 20 is rotatably mounted, and with a second lug 21 arranged to serve as a bearing projection for the lower end of said screw; it will be understood that suitable provision is made to prevent lengthwise movement of the adjusting screw 20 in the lug 19, without interfering with the rotation of said screw 20 therein. As shown in Figs. 1 and 2, a hand wheel 23 or equivalent device may be provided on the adjusting screw 20 to facilitate the manipulation thereof. The aforesaid screw 20 passes through and is in threaded engagement with the head 18 so that an operation of said screw 20 will slidably adjust the carrier 16 on said head 18 in vertical directions; as shown in Fig. 2, one or more set screws 24 or any equivalent suitable means may be provided for fixing the upper carrier 16 in an adjusted position on the head 18.

In the illustrated example the head 18 and the upper carrier 16 with the stamping or pressure member 17 thereon is vertically reciprocated in synchronism with the associated elements of the apparatus by means of a rocking lever 25 pivoted at 26 and having its one end pivotally connected at 27 with said head 18, as shown in Fig. 2; for the purpose of rocking the lever 25 on its pivot 26, the other end of said lever 25 may carry a roller 28 projecting into a cam groove 29 of a cam disk 30 fixed upon a shaft 31 suitably journaled in the arms 13. In order to permit the upper carrier 16 and its associated elements to reciprocate in a straight vertical path in the guide plate 14 without jamming as a result of the rocking of the lever 25 in an arc, the pivot 26 may be carried by members 32 which depend from a pivot 33 mounted on the arms 13, as shown in Figs. 2 and 4. It may be desirable at times to vary the vertical movements of the stamping or pressure member 17 for the purpose for instance of adjusting the effective pressure developed thereby; the pivot 33 in the form of a shaft journaled in the arms 13 may accordingly be provided with eccentrics 34 located within circular bearing rings 35 with which the members 32 in such case are provided. As illustrated in Fig. 1, the means for actuating the eccentrics 34 may consist of an operating lever 36 pivoted at 37 on an arm 13 and connected by means of a link 38 with a crank-arm 55

39 which is fixed upon and projects radially from the pivot shaft 33.

As shown in Fig. 2, the bed plate 12 is provided with an opening 40 beneath and in registry with the stamping or pressing member 17, the latter being located in vertical registry with a lower carrier 41 adapted to reciprocate in opposed relation to the upper carrier 16, as shown in Fig. 2. The lower carrier 41 is vertically slidable in a stationary upright guide frame 42 suitably secured in proper position between the side members 10 as by means of supporting flanges 42^a bolted to said side members 10, as shown in Fig. 5; said lower carrier 41 may be vertically reciprocated in said guide frame 42 in properly timed relation with the upper carrier 16 and its associated elements, by means of any suitable mechanism. In the illustrated example the latter consists of a rocking lever 44 carried by a shaft 45 rotatably mounted on the side members 10 and having its one end forked at 46 for slidable engagement with a bearing block 47 fixed upon a pivot pin 48 journalled between lugs 49 forming part of or secured to the lower carrier 41, as shown in Fig. 2. Any suitable means may be embodied in the apparatus for operatively rocking the lever 44 as by providing the latter at its opposite end with a roller 50 projecting into the cam groove 51 of a cam disk 52 mounted to rotate with a shaft 53 journalled on the side members 10 in any convenient manner.

The novel machine is designed to operate with printing or impression slugs 54 which carry the individual items to be printed, as exemplified for instance by means of different persons, in the form of type cast upon the upper faces of said slugs in any customary way; it will be understood that the type on the slugs 54 is always of a character to accord or harmonize with the previously printed matter to which the items are to be added by the apparatus. The slugs 54 are fed and bodily transferred to the lower carrier 41 for movement therewith, and removed therefrom in succession in a manner to be more fully described hereinafter. The lower carrier is suitably constructed to removably accommodate the successive slugs 54 on its upper end and to convey the said slugs 54 in individual succession to and from the printing position in which, in co-operation with the stamping or pressure member 17, impressions are made thereby. In the illustrated example, the lower carrier 41 is accordingly provided with gripping means of suitable construction and arrangement to provide the desired results. As shown in the drawings, the aforesaid gripping means may consist of a plate or stop 55 fixed upon the lower carrier 41 and projecting above the upper face thereof, and a movable clamping member 56 located in spaced opposed relation to said plate 55 and carried by a frame 57 pivoted at 58 between the lugs 49 of said carrier 41, as shown in Fig. 3; the clamping member 56 is resiliently controlled by a spring 59 which bears against the frame 57 and yieldingly forces said clamping member 56 in a direction toward the plate or stop 55. With this arrangement, the spring 59 by acting on the frame 57 serves to force the clamping member 56 into engagement with the successive slugs 54 for clamping the same against the plate or stop 55 during the printing operations. The successive slugs 54 will be removed at the proper time from the lower carrier 41 in the manner to be more fully set forth hereinafter, it being understood that the spring controlled clamping member 56 will not prevent such

removal, although it firmly secures successive slugs 54 in place on the lower carrier 41 for movement therewith to and from the printing position and during the actual printing operation. In certain classes of personalized printing work, the items to be added to the previously printed matter include items which are to be repeated in combination with the impressions made by successive slugs 54. To provide for such contingencies, the lower carrier 41 may be provided at its upper end with a fixed vertical projection or plate 60 located in spaced parallel relation to the plate or stop 55 and forming therewith a groove for the reception of type or slugs 61 secured in place in any suitable manner as by one or more set screws 62. To still further increase the facilities of the apparatus, the clamping member 56 may itself be provided at its upper end with a groove for the accommodation of additional type or slugs 63; the latter also may be fixed in position in the groove of the clamping member 56 in any convenient manner as by means of one or more set screws 64. It will be understood that the type or slugs 61 and 63 exemplify the matter which is to be repeated in association with successive slugs 54, and that in the illustrated example each operation of the lower carrier 41 to the printing position will result in impressions from the type or slugs 61 and 63 in predetermined relation to the coincidental impression from the slugs 54 which are successively transferred to the lower carrier 41. The type or slugs 61 and 63 will always make impressions according or harmonizing with the impressions made by the slugs 54 and with the previously printed matter to which the items are added.

In order to relieve the mechanism whereby the lower carrier 41 is reciprocated, from excessive strains during the successive printing operations, and to enable the lower carrier 41 to resist the pressure developed during the actual printing steps to thereby produce uniform and efficient impressions from the successive slugs 41 and from the type or slugs 61 and 63 when the latter are present, the machine is provided with means whereby said carrier 41 is supported from below during each printing stage. In the illustrated example the aforesaid supporting means is exemplified by an arm 65 fixed upon a pivot shaft 66 journalled in the supporting flanges 42^a, as shown in Fig. 5, and provided with a shoulder 67 arranged to extend beneath the lower carrier 41 when the latter is in its raised position, said arm 65 having its upper end movable in an opening 68 in the guide frame 42 as shown in Figs. 2 and 5. The arm 65 may be automatically operated in any suitable manner to remove the shoulder 67 from beneath the raised carrier 41 at the proper time, as for instance by means of a link 69 pivotally connected at 70 with the aforesaid arm 65 and at 71 with a lug 72 fixed upon a pivot pin 73 which also carries a tripping pawl 74 and is rotatably mounted in a bearing 75 upon the base plate 11; the tripping pawl 74 projects into the path of a projection 76 carried for instance by a cam disk 77 fixed upon the shaft 53, as shown in Fig. 2.

The apparatus further includes a container for a supply of slugs 54, said container being illustrated in the form of a horizontal chute 78 extending lengthwise of the one side member 10, as shown in Fig. 3, and dimensioned transversely in accordance with the length of the slugs 54 which said chute 78 is designed to accommodate. The chute 78 is suitably supported in the machine 75

and terminates at its delivery end in registry with transferring means and adjacent to an opening 79 formed in the aforesaid side member 10, the inner wall *a* of said chute 78 being provided with a transverse extension 80 as illustrated in Fig. 3. In the example shown, a guide member 81 is located and suitably supported in transverse relation to the delivery end of the chute 78 and projects through the opening 79 beneath the transverse extension 80 of the inner wall *a* of said chute 78 into delivery relation to the lower carrier 41 when the latter is in its normal lowered position as shown in Figs. 2, 3 and 5. In practice the bottom of the chute 78 may be transversely extended to form the guide member 81 as illustrated in Fig. 3. The guide member 81 is preferably provided with an upright guide wall 82 which extends lengthwise thereof and across the delivery end of the chute 78 at a distance 20 therefrom with the one end of said guide wall 82 terminating in spaced parallel relation to the transverse extension 80 of the inner wall *a* of said chute 78 as shown in Fig. 3; in the preferred arrangement the distance between the extension 25 80 and the guide wall 82 corresponds approximately to the transverse dimension of the individual slugs 54 to provide a passage for directing the latter to the lower carrier 41. With the aforesaid arrangement, the guide member 81 and the guide wall 82 serve to guide and maintain the transferring means in its intended operative path, as will appear more clearly hereinafter.

The aforesaid transferring means, in its illustrated form, consists of a member 83 slidably mounted on a guide rod 84 extending lengthwise in parallel relation to the guide wall 82 and mounted in position thereon in any convenient manner as by means of brackets 85, as illustrated in Figs. 3 and 5. The member 83 carries 40 an upwardly projecting arm 86 which is secured to a block 87 slidable in a slot 88 extending lengthwise of the guide wall 82, said block 87 in turn being fastened to a transfer device or plate 89 slidable along the inner face of the guide wall 82 as shown in Fig. 3; to facilitate the assembling and, if necessary, the disassembling of the parts, the connection between the block 87 and the transfer device or plate 89 is preferably of an 45 easily detachable type as exemplified for instance by the headed screw 90 shown in Fig. 8.

Any suitable mechanism may be provided for reciprocating the member 83 lengthwise of the guide rod 84 to correspondingly operate the transfer device or plate 89 lengthwise of the guide wall 50 82 in transverse relation to the chute 78 to transfer successive slugs 54 from said chute 78 to a printing position on the lower carrier 41 for movement therewith, as will be more fully described hereinafter. In the preferred arrangement, the aforesaid mechanism includes a lever 91 pivoted at 92 upon a bracket 93 suitably mounted upon the one side wall 10, said lever 91 being pivotally connected with the previously mentioned transferring means in a novel manner to 55 permit the connection to be automatically broken without injury to the parts if this should become necessary for any reason, such as the development of unexpected resistance to the operation of said transferring means. In the illustrated example, the lever 91 is provided at its free end with a hooked detent or latch 94 pivoted at 95 on said lever 91 and yieldingly controlled by a suitable spring 96 as illustrated in Fig. 9. In the 60 normal operative condition of the connection, the 75 detent or latch 94 engages a pin or projection 97

carried by an arm 98 pivotally mounted at 99 upon a lug 100 depending from the member 83 as shown in Figs. 8 and 9; to increase the yieldability of the connection and to thereby avoid premature or undesired breakage thereof, the 5 arm 98 is preferably influenced by a coil spring 101 or its equivalent as illustrated in Fig. 8. The lever 91 is oscillated on its pivot 93 in a manner to reciprocate the transfer device or plate 89 in its operative path lengthwise of the guide wall 10 10 82, by means of a cam 102 fixed upon the shaft 53 and including a cam-groove 103 for the accommodation of a roller 104 rotatably mounted upon the lever 91 as shown in Fig. 1 and by dotted lines in Fig. 3. 15

In addition to the parts so far described, the machine includes intermittently actuated means for advancing the supply of slugs 54 in the chute 78 in successive steps in a manner to bring successive forward terminal slugs 54 into operative 20 relation to the transferring means to permit said slugs 54 to be individually shifted from said chute 78 to a printing position on the lower carrier 41 for operative movement therewith.

As shown by way of example in the drawings, 25 the aforesaid intermittently actuated means includes an advancing member 102^a located centrally in the chute 78 in transverse relation thereto and arranged to engage the rearward terminal slug 54 of the supply contained in said chute 74 as 30 shown in Fig. 3. The advancing member 102^a is riveted or otherwise fastened to the depending section of an angular bracket 103^a carried by a lever 104^a extending horizontally in transverse horizontal relation to the chute 78 and across and 35 outwardly beyond the outer wall *b* thereof as illustrated in Figs. 3 and 6; to facilitate manipulation of the lever 104^a for the purpose to be more fully set forth hereinafter, said lever 104^a preferably terminates at its outer end in or is provided 40 thereat with a suitable handle 105. At an intermediate point in registry with the outer wall *b* of the chute 78 the lever 104^a is secured to a slide block 106 which depends therefrom into a groove 107 extending lengthwise of said outer wall *b* as 45 shown in Fig. 3; the arrangement is such that the slide block 106 is capable of readily traveling lengthwise of the groove 107 as will appear more fully further on in the description. A plate 108 is conveniently fastened in surface engagement 50 with the upper face of the outer wall *b* of the chute 78 and is provided with a longitudinal slot 109 preferably of relatively less transverse width than the corresponding dimension of the groove 107; as shown in Fig. 6, the slot 109 is in off-set 55 registry with the groove 107 and in combination therewith provides an undercut groove as is clearly shown in Fig. 6. At the same time the slide block 106 is provided along its lower edge with a longitudinal rib 106^a which projects beneath the plate 108 and maintains the slide block 106 in the groove 107. In addition to its other 60 functions, the slide block 106 serves as a fulcrum for the lever 104^a to permit manual adjustment of the advancing member 102^a lengthwise of the 65 chute 78 to different positions therein for proper co-operation with varying members of slugs 54 in said chute 78; if for any reason it should become necessary or desirable to remove the slide block 106 from the groove 107, this may be readily accomplished by properly tilting the lever 104^a in a vertical direction to enable the rib 106^a to 70 pass upwardly out of the slot 109 of the plate 108.

The feeding mechanism for intermittently advancing the member 102^a to correspondingly ad- 75

vance the slugs 54 in the chute 78 is arranged to avoid the development of any feeding strains tending to bind the slugs 54 in said chute 78 or to otherwise interfere with the efficient intermittent advance thereof. In its illustrated example, the aforesaid feeding mechanism accordingly includes an endless sprocket chain 110, the upper run of which is movable in a slot 111 extending lengthwise of the bottom of the chute 78 in registry with the longitudinal center line thereof. As shown in Fig. 6, the aforesaid upper run of said chain 110 does not project upwardly beyond said bottom of the chute 78 and is supported against sagging on a plate 112 removably secured to the lower surface of the bottom of said chute 78 in registry with the slot 111 thereof; in the preferred construction the plate 112 may be provided with a longitudinal recess 113 for the accommodation of said upper run of the sprocket chain 110. It will be understood that the sprocket chain 110 may be replaced by equivalent means if this should be desired, and that said chain 110, while preferred, is intended to exemplify endless devices suitable for the purpose.

The sprocket chain 110 passes over a relatively small sprocket wheel 114 carried by a shaft 115 journaled near one end of the slot 111 in a bearing frame 116 depending from the guide member 81 at a distance from the guide wall 82 thereof. In addition the sprocket chain 110 further passes over a second sprocket wheel 117 which, in the illustrated example, is of larger diameter than the sprocket wheel 114 and is mounted on a shaft 118 journaled in bearings 119 depending from the chute 78 near the opposite end of the slot 111, as shown in Fig. 1. It will be understood that the sprocket wheels 114 and 117 are both located in registry with the slot 111 so as to maintain and shift the upper run of the sprocket chain 110 therein in the intended manner.

For the purpose of detachably connecting the advancing member 102^a and its associated elements with the upper run of the sprocket chain 110 or its equivalent, the depending section of the angular bracket 103^a may be provided with a downwardly projecting finger or lug 120; the latter is adapted to be inserted into a link of the chain 110 at the selected point of the upper run thereof at which the connection is to be made as illustrated in Figs. 6 and 8.

Any suitable mechanism may be provided for intermittently actuating the sprocket chain 110 or its equivalent to cause the upper run thereof to correspondingly actuate the advancing member 102^a in a manner to effect the intermittent advance of the slugs 54 toward guide member 81 for successive delivery to the lower carrier 41. As illustrated in Fig. 1 the aforesaid mechanism may consist of a ratchet wheel 121 fixed upon the shaft 118 and arranged to be rotatably actuated by means of a pawl 122. The latter is pivotally connected at 123 with an arm 124 projecting radially outward from a bearing 125 illustrated in Fig. 7 and loosely mounted on the shaft 118; gravity may be relied upon to maintain the pawl 122 in operative engagement with the ratchet wheel 121, or a spring may be provided for this purpose in any conventional manner. A second arm 126 extends radially downward from the bearing 125 and in the illustrated example is pivotally connected at 127 with a link 128 telescopically combined with an operating member 129; a coil spring 130 is located between an annular flange 131 of the link 128 and a corresponding flange 132 of the operating member

129 and serves to impart resiliency to the bi-partite actuating device 128-129. The operating member 129 is formed with a slot 133 whereby said member 129 is slidably mounted on the shaft 53, and carries a roller 134 for periodic engagement by a cam 135 fixed upon said shaft 53 as shown in Fig. 1. With this arrangement, the cam 135 will be operated in a rotary path and by periodical engagement with the roller 135 will force the bi-partite actuating device 128-129 to the left in Fig. 1 to rock the bearing 125 on the shaft 118 and swing the arm 124 in a direction to cause the pawl 122 to rotatably operate the ratchet 121 one step. This step rotation will be imparted to the shaft 118 and sprocket wheel 117 and accordingly will cause the upper run of the sprocket chain 110 to move linearly in the slot 111 and to carry with it the advancing member 102; this movement of the latter will be transmitted to the slugs 54 and will shift the latter lengthwise of the chute 78 to an extent sufficient to bring the front terminal slug 54 into position for transfer to the lower carrier 41. As the cam 135 passes beyond the roller 134 the parts will be moved in the reverse direction by the action of the spring 130 and thereby will cause the pawl 122 to travel over the teeth of the ratchet wheel 121 in a movement of recovery ready for the next operative step to again advance the upper run of the chain 110 in the slot 111. To control the aforesaid movement of recovery of the pawl 122 and its associated elements, the bearing 125 may be provided with a plate 125^a lying in surface engagement therewith and provided with a third radially projecting arm 136 arranged to engage a fixed stop 137 to thereby arrest the return movement of the parts as shown in Fig. 1; to provide for adjustment of the arm 136 the plate 125^a may include an arcuate slot 138 for the accommodation of a set screw 139 carried by the bearing member 125 and adapted to maintain the plate 125^a in its adjusted operative relation to said ratchet wheel 121. In order to maintain the sprocket chain 110 or its equivalent against undesired slackness, a suitable tension means may be provided. In the drawings, this tension means is exemplified by a tension roller 140 over which the lower run of the chain 110 or its equivalent passes as illustrated in Fig. 1; the tension roller 140 is carried by a shaft 141 adjustably mounted in a slotted frame 142 depending from the chute 78 as shown in Fig. 1, suitable provision being made for fixing the roller 140 and its shaft 141 in an adjusted position.

In the instant machine after a printing operation has been effected by a given slug 54, the latter is removed from the printing position on the lower carrier 41 by the next successive slug 54 as it is shifted into printing position on said carrier 41 in the manner to be more fully set forth hereinafter.

For the purpose of disposing of the slugs 54 in an orderly manner as said slugs are removed from the lower carrier 41, the machine is provided with an inclined chute 143 suitably mounted on the machine in receiving relation to the lower carrier 41 when the latter is in its normal position, and in delivery communication with an inclined trough 144 or its equivalent; as shown in Figs. 4 and 5, the chute 143 and trough 144 extend at an inclination downwardly from the one side member 10 so that successive slugs 54 subsequent to their removal from the lower carrier 41 will slide downwardly through the

chute 143 to a position in the trough 144. As the slugs 54 are thus successively deposited in the trough 144 said slugs are progressively shifted lengthwise of said trough for removal therefrom at will in any convenient manner. In the illustrated example of the machine, this shifting of the slugs 54 is accomplished by means of a pushing member 145 normally located at one end of the trough 144 in operative relation to the chute 143 as shown in Figs. 3 and 5. The pushing member 145 is carried by a member 146 fixed upon a support 147 provided with a recess for the accommodation of a rib 148 located upon the lower surface of the trough 144 for guiding said support 147 in its operative movements; the support 147 further is slidably mounted upon a guide rod 149 projecting from a supporting member 150 whereby the chute 143 and trough 144 are supported as shown in Figs. 3 and 5. A link 151 has its one end pivotally connected at 152 with the support 147 and its other end pivotally secured at 153 upon a block 154 slideable in the groove 155 of a crank member 156 fixed upon the shaft 53 as illustrated in Figs. 2 and 3. With this construction, the extent of reciprocation of the link 151 and the operative movements of the pushing member 145 may be selectively varied to meet existing conditions by adjusting the position of the block 154 in the groove 155 of the crank member 156. Suitable provision is made for fixing the block 154 in its adjusted position in the groove 155; for instance, the pivot 153 may be in the form of a threaded pin adapted to receive a nut 157 which clamps the block 154 in place without interfering with the pivotal movements of the contiguous end of the link 151 on the pivot 153.

In practice it sometimes happens that the slugs 54 in the chute 78 temporarily cling to each other and interfere with the transfer of a front terminal slug 54 by the transfer device 89 to the lower carrier 41. To overcome this interference, if and when it develops, the apparatus is provided with means for periodically impacting successive front terminal slugs 54 in the chute 78 or in the guide member 81 to thereby agitate said slugs 54 and disconnect any slugs 54 which may temporarily cling together. In the illustrated example, the aforesaid agitating means comprises a lever 158 pivoted at 159 upon one of the flanges 42^a as illustrated in Figs. 2 and 5; the lever 158 at its lower end carries an impact screw 160 or equivalent projection, located in the path of a bracket 161 rigidly secured to the arm 65 as illustrated in Figs. 2 and 5. At its upper free end the lever 158 carries a pin 162 which is movable in a slot 163 provided in the one side member 10, as shown in Fig. 2, said pin 162 projecting through said slot 163 into the guide member 81. With this arrangement, each time the arm 65 is pivotally actuated to release the lower carrier 41 for downward movement, the bracket 161 will strike the impact screw 160 or its equivalent and swing the lever 158 on its pivot 159 to cause the pin 162 to impact and agitate the front terminal slug 54 prior to its engagement by the transfer device 89; the aforesaid impact of the pin 162 serves to agitate the slugs 54 to an extent sufficient to disconnect the front terminal slugs 54 if it should adhere to the next succeeding slug 54.

The machine further includes means for inking the type located on the slug 54 which is located on the lower carrier 41 for movement therewith to the printing position, said inking means being of any suitable type and operating in properly

timed relation with the other elements of said machine. In its illustrated form, the inking means comprises a frame 164 mounted on rollers 165 adapted to travel lengthwise of guide rails 166 located in opposed parallel relation and fixed upon the inner faces of the side members 10 as shown in Figs. 2 and 4. Inking rolls 167 and 168 are rotatably supported upon the frame 164 by being journaled in the side members thereof, while a third roller 169 is mounted on said frame 10 in a specific manner to be more fully described hereinafter. The inking rolls 167 and 168 are continuously in rolling engagement with actuating rolls 170 while the inking roll 169, in its operative position, is also in rolling contact with one 15 of said actuating rolls 170 as illustrated in Fig. 2. The actuating rolls 170 are carried by shafts 171 which are rotatably mounted preferably in upwardly open recesses formed in the side members of the frame 164, so as to be readily removable 20 therefrom at will. The shafts 171 of the actuating rolls 170 carry suitable pinions which mesh with stationary racks 172 secured in proper position in the apparatus in any convenient manner. With this arrangement, as the frame 164 is propelled lengthwise of the guide rails 166, the aforesaid pinions will roll along and be rotated by the racks 172 to correspondingly rotate the actuating rolls 170; as a result the latter because of their frictional surface engagement with the inking 25 rolls 167, 168 and 169, will cause said inking rolls to be rotated upon their several axes to thereby bring about an efficient inking of said rolls 167, 168 and 169 and an efficient distribution of the ink thereby upon the type of the slug 54 30 clamped upon the lower carrier 41 at the time. Ink is supplied to the surface of the roll 169 by means of a transfer roll 173 when the frame 164 is in the retracted position illustrated in Fig. 2, said transfer roll 173 being removably journaled 40 in bearing brackets 174 and arranged to receive a surface coating of ink from a distributing roll 175 removably journaled in an ink reservoir 176 supported upon an auxiliary bed plate 177 extending between and suitably secured to the side members 45 10 as shown in Fig. 4. To regulate and control the coating of ink picked up by the distributing roll 175 from the supply in the reservoir 176, a doctor or scraper 178 may be mounted in the reservoir 176 in tangential surface engagement with the roll 175 as illustrated in dotted lines in Fig. 2; the doctor or scraper 178 may be controlled by an adjusting screw 179 for the purpose of adjusting the active edge of said doctor 178 relatively to the surface of the roll 175. It will be understood that 50 in the operation of the inking means, the ink is distributed by the roll 175 to the transfer roll 173 and by the latter to the inking roll 169 each time the latter contacts with said roll 173 in the retracted position of the frame 164; the inking rolls 167 and 168 in turn receive coatings of ink 55 through the medium of the actuating rolls 170 as will be apparent.

In the illustrated example of the apparatus the distributing roll 175 is intermittently rotated 60 in the reservoir 176 by means of a pinion 180 fixed upon the shaft of the roll 175 in mesh with a second pinion 181 carried by a shaft 182 suitably journaled in the one side member 10. The pinion 181 is actuated by means of a ratchet wheel 183 65 fixed upon the shaft 182 and rotatably advanced in successive steps by means of a pawl 184 pivotally mounted on an oscillating lever 185 and yieldingly maintained in engagement with the ratchet wheel 183 by means of a spring in any 70 75

conventional manner. The lever 185 is loosely mounted for pivotal movement on the shaft 182 and is provided with a longitudinal slot 186 as shown in Fig. 1; a link 187 is pivotally connected 5 at one end with the lever 185 by means of a suitable clamping means adjustable lengthwise of the slot 186 and including an easily manipulated nut 188 whereby the clamping means is fixed in its adjusted position in the slot 186 without interference with the pivotal movements of the contiguous end of the link 187. At its opposite end, the latter is pivotally connected at 189 with an upright operating member 190 pivotally attached at 191 to one of the side members 10 and carrying 10 a roller 192 at its upper end, as illustrated in Fig. 1. The operating member 190 is rocked on its pivot 191 by means of a suitable cam 193 fixed upon the shaft 53, provision being made in any conventional manner to maintain the roller 192 in rolling contact with said cam 178. With the illustrated arrangement the cam 193 as it rotates with the shaft 53 will rock the operating member 190 on its pivot 191 and through the medium of the link 187 will correspondingly oscillate 15 the lever 185. The pawl 184 will thereby be caused to alternately develop operative movements and return movements whereby the ratchet wheel 183 is rotatively operated in successive steps. This periodical operation of the ratchet wheel 183 will be communicated to the pinion 181 and in turn transmitted thereby to the pinion 180 whereby the distributing roll 175 will be intermittently rotated in the reservoir 176. The extent of rotative movement imparted to the distributing roll 175 each time the pawl 184 actuates, the ratchet wheel 183 may be varied and regulated at will by shifting the clamping means 188 lengthwise of the slot 186.

To still further increase the efficiency of the inking mechanism, the inking rolls 167, 168 and 169, during the reciprocation of the frame 164, are caused to pass over and in rolling contact with the upper surface of an inking platen 194 whereby the ink is evenly distributed over the 40 peripheral surfaces of said inking rolls 167, 168 and 169. The platen 194 is carried by an upright shaft 195 rotatably mounted in an upright bearing 196 projecting upwardly from the auxiliary bed plate 177, as shown in Figs. 2 and 4. For the purpose of intermittently rotating the platen 194, the shaft 195 carries a ratchet pinion 197 arranged to be rotatively actuated in successive steps by means of an operating pawl 198 shown best in Fig. 3. The pawl 198 is pivotally mounted on the upper end of an upright lever 199 pivoted at 200 upon lugs 201 projecting upwardly from the base-plate 11, as illustrated in Figs. 2 and 4; any suitable type of spring as shown for instance at 202 may be provided for 45 yielding maintaining the pawl 198 in engagement with the ratchet pinion 197. The lever 199, in the arrangement shown in the drawings, is provided with a cam projection 203 of suitable form arranged to be acted on by a roller 204 rotatably carried by the rocking lever 44, each time the latter operates the lower carrier 41 in vertical directions; a coil spring 205 surrounds the pivot 200 of the lever 199 and develops a tension on the latter tending to hold said lever 199 in operative 50 engagement with the roller 200 at all times. It will be obvious with the arrangement set forth that, as the rocking lever 44 is actuated to vertically operate the lower carrier 41, the roller 204 by acting on the cam projection 203 will rock 55 the lever 199 on its pivot 200 and accordingly will

cause the pawl 198 to rotate the ratchet pinion 197 in successive steps to thereby correspondingly rotate the platen 194.

Due to the fact that the actuating rolls 170 are geared to the racks 172 and in frictional contact with the inking rolls 167, 168 and 169, and because the inking roll 169, when the frame 164 is in its retracted position, is in frictional engagement with the transfer roll 173 which in turn is in surface contact with the distributing roll 175, this entire train of rolls is in geared connection with said racks 172 at the time the frame 164 is near the terminus of its rearward movement. Unless provision is made to temporarily release said train of rolls from the restraining effect of its geared connection with the racks 172, it is quite obvious that the operation of the distributing roll 175 by its actuating mechanism will be opposed when the frame 164 reached a position in which the transfer roll 173 engages the inking roll 169, and that injury to the mechanism or disturbance of its operation may result. To avoid this possibility the inking roll 169 is journaled in bearing members 206 pivoted upon the side members of the frame 164 and carrying rollers 207 which throughout the major portion of the movements of said frame 164 and its associated elements are arranged in rolling engagement with members 208 suitably fixed in place and extending lengthwise of the racks 172 as 20 illustrated in Fig. 2. The bearing members 206 are acted on in any convenient manner by springs tending to force said rollers 207 in an upward direction. As shown in Fig. 2, the members 208 are formed with recesses 209 located in registry 25 with the paths of travel of the rollers 207 and adapted to receive said rollers when the frame 164 reaches the end of its return movement. When the rollers 207 pass into said recesses 209 the bearing members 206 will be pivotally actuated by their springs in a direction to shift the inking roll 169 out of surface contact with the one actuating roll 170 so that at this stage the inking roll 169, the transfer roll 173 and the distributing roll 175 are no longer in geared connection with the racks 172 and accordingly are 30 free to rotate independently of the rolls 167, 168 and 170. As soon as the rollers 207 pass out of the recesses 209 when the frame 164 begins an operative movement, the bearing members 206 will be pivotally operated against the tension of their springs to return the inking roll 169 into surface engagement with the one actuating roll 170 and to restore it as part of the train of rolls in geared connection with the racks 172; it will be understood that when this occurs, the inking roll 169 has been carried out of engagement with the transfer roll 173 by the forward movement of the frame 164 on the guide rails 166. 35

The reciprocation of the frame 164 on the 40 rails 166 in proper operative synchronism with the other elements of the machine may be accomplished by means of any suitable mechanism, an example of which is shown in the drawings. In its illustrated form this mechanism comprises 45 racks 210 slidably mounted in guides 211 supported at opposite sides of the machine on the respective side members 10 in any suitable manner. The racks 210 are connected with the side members of the frame 164 by preferably releasable couplings or links 212 pivoted at 213 on said side members of the frame 164 as shown in Fig. 2. The racks 210 furthermore mesh with toothed segments 214 fixed upon a shaft 215 journaled in the side members 10 and carrying a lug 216 50

which is pivotally connected at 217 with an operating member 218 operated by a suitable cam on the shaft 53, said cam being arranged to rock the segments 214 through the medium of the operating member 218 in a manner to reciprocate the racks 210 and thereby correspondingly operate the frame 164 and its associated elements.

The machine as a whole may be operated by any conventional form of driving mechanism as exemplified by the belt 219 and pulley 220, the latter being fixed upon a drive shaft 221 rotatably mounted on the side members 10. The shaft 221 carries a pinion in mesh with a gear 222 fixed upon a countershaft 223 journaled in the side members 10 and provided with a pinion 224 arranged in mesh with gears 225 and 226 secured respectively upon the shafts 31 and 53 as indicated diagrammatically in Fig. 2.

For the purpose of simplifying the explanation of the operation of the apparatus and without in any sense intending thereby to limit the scope thereof, it will be assumed that the slugs 54 are provided with lines of type representing the names of selected individuals. It will be understood that the aforesaid lines of type are located on the slugs 54, in each instance, so as to occupy the proper printing position when said slugs 54 are in place on the lower carrier 41 for movement therewith to effect the impressions; as previously stated, the type on said slugs 54 is always of a character to accord or harmonize with the previously printed matter to which the items are to be added by the apparatus.

In practice a supply of slugs 54 is contained in the chute 78 in adjacent relation to each other, with the advancing member 102 in engagement with the rearmost terminal slug 54 as shown in Fig. 3. If it should be necessary to disconnect the advancing member 102 from the chain 110 or its equivalent, in order to adjust said member 102^a into contact with the aforesaid terminal slug 54, this may be easily accomplished by simply pressing downwardly on the handle 105 in Fig. 6. This will rock the lever 104^a with the slide block 106 acting as a fulcrum in the groove 107 and consequently will lift the finger or lug 120 out of engagement with the upper run of the sprocket chain 110. With the parts in this condition, the slide block 106 is free to slide lengthwise of the groove 107 to thereby shift the advancing member 102^a lengthwise of the chute 78 into proper engagement with the rearmost terminal slug 54. When this adjustment has been effected, the lever 104^a is rocked in the return direction to re-insert the finger or lug 120 into a link of said upper run of the chain 110; the advancing member 102^a is thus again connected with the feeding mechanism whereby the slugs 54 are intermittently advanced in the chute 78 for successive transfer to the lower carrier 41. With the aforesaid arrangement, the advancing member 102^a may readily be adjusted to any position in the chute 78 for proper co-operation with the slugs 54 regardless of the number thereof within the capacity of said chute 78. If for any reason it should be desired or become necessary to completely remove the advancing member 102^a and its associated elements from the apparatus, this may be done by swinging the handle 105 downwardly in Fig. 6 to a position which permits the rib 106^a of the slide block 106 to pass upwardly out of the slot 109.

In describing the operation, it will be assumed that in Figs. 2 and 3 the apparatus is in a position subsequent to the printing of the name or

its equivalent carried by the slug 54 which is in printing position on the lower carrier 41; it will be understood that the associated slugs or type 61 and 63, if present on the carrier 41, will coincidentally have made impressions in associated relation to the impression made by the particular slug 54. At this stage as shown in Fig. 3, the transfer device or plate 89 is in position to transfer the next succeeding slug 54 from the guide member 81 to the printing position on the lower carrier 41 and at the same time to remove the preceding slug 41 therefrom.

As the apparatus continues in operation, the lever 91 will be swung on its pivot 92, by the action of the cam-groove 103 on the roller 104, in a direction to shift the transfer device or plate 89 lengthwise of the guide wall 82 in a downward direction in Fig. 3. This movement of the transfer device or plate 89 will be transmitted to the front terminal slug 54 and will shift the latter through the space between the extension 80 and guide wall 82 into end to end contact with the preceding terminal slug 54 which at this stage is carried by the lower carrier 41. As these operations continue, the previously printed slug 54 will be forced from the lower carrier 41 and will finally be replaced thereon by the next succeeding slug 54, as will be apparent; as the preceding slug 54 is thus removed from the lower carrier 41, it will pass down the inclined chute 143 into the inclined trough 144. In proper synchronism with the other mechanism, the pushing member 145 will be actuated by the link 151, the crank member 156 and associated elements to shift the slug 54 lengthwise of the trough 144 out of the way of the next succeeding slug when the latter is likewise removed from the lower carrier 41. It will be understood that the operative force of the transfer device or plate 89 whereby the removal of one slug 54 from the lower carrier 41 by the next succeeding slug 54 is accomplished, is sufficient to overcome the resilient clamping action of the clamping member 56; it is further to be understood that the resistance to the removal of a slug 54 from the lower carrier 41 interposed by the clamping member 56 is not sufficient to break the connection between the lever 91 and the transfer device or plate 89. If, however, for any reason unexpected resistance to the transfer of one slug 54 from the guide member 81 to the lower carrier 41 and the coincidental removal therefrom of the next preceding slug 54 should develop, the pin or projection 97 will be automatically disconnected from the detent 94 which will yield under such circumstances as is clearly apparent in Fig. 9; when this occurs, the transferring means is automatically disconnected from the operating means and injury to the parts is accordingly prevented. It is, of course, obvious that the detent 94 must be again connected with the pin 97 before the operation of the apparatus is continued to thereby restore the connection between the transfer device 89 and the operating lever 91.

When the replacement of the slugs on the lower carrier 41 has taken place and the transfer device or plate 89 has been returned to its normal position to await subsequent operation by the cam groove 103 and cooperating elements, the apparatus is ready to effect the printing step.

Previous to the aforesaid operations or at any appropriate period thereof, the sheet of paper or equivalent material on which the printing is to be done by the slugs or type 61 and 63, if pres-

ent, and by the particular slug 54 located at the time on the lower carrier 41, has been placed in proper position upon the bed plate 12 with the space in which the items of said slugs 54, 61 and 63, are to be printed in registry with the opening 40 therein.

In proper synchronism with the above operations, the operating member 218 operated by its cam in the shaft 53 will rock the shaft 215 to swing the segments 214 in a direction to cause the racks 210 to gradually shift the frame 164 lengthwise of the guide rails 166 toward the left in Fig. 2. During this travel of the frame 164, the inking rolls 167, 168 and 169 to which ink has been transferred from the transfer roll 173, will be rotated about their axes through the medium of the actuating rolls 170 operated by their pinions in co-operation with the racks 172; in the movement of the frame 164 lengthwise of the guide rails 166 in the manner described, the inking rolls 167, 168 and 169 will pass over and in surface contact with the inking platen 194 so that the surface of said rolls 167, 168 and 169 will become evenly coated with printing ink. The operations are so timed that the inking rolls 167, 168 and 169 will successively pass over and in contact with the line of type located on the slug 54 which is fixed upon the lower carrier 41 at the time, and over and in contact with the type 30 of the adjacent slugs 61 and 63, if present, to apply a coating of ink to said lines of type for printing purposes; the frame 164 and the elements carried thereby will be shifted in a return direction to a sufficient degree to move the 35 inking rolls 167, 168 and 169 backward beyond the vertical path of the carrier 41 before upward movement of the latter has commenced. After the inking of the slug or slugs on the carrier 41 has been finished, the rocking levers 25 and 44 will be rocked on their pivots in inverse relation by the cam grooves of their respective operating cams. As a result the upper carrier 16 will be moved downwardly to correspondingly move the pressure member 17, while the lower carrier 41 45 with the slug 54, and the slugs 61 and 63, if present, will simultaneously be adjusted in an upward direction to carry said slugs to the printing position. The arrangement is such that the stamping or pressure member 17 will engage the upper surface of the paper or other material which is to receive the impressions at approximately the same moment that the lines of type on the slugs located on the carrier 41 engage the lower surface of said sheet at the point at which 50 the impression or impressions are to be made. It will be understood that the upper carrier 17 has previously been adjusted by means of the adjusting screw 20 or its equivalent to set the stamping or pressure member 17 in a position for co-operation with the printing slug 54 and the associated slugs 61 and 63, if present, to produce efficient and satisfactory impressions therefrom. As the lower carrier 41 is moved upwardly, the shoulder 67 of the arm 65 will pass beneath the 55 lower end of said carrier 41 and thereby serve to support the lower carrier 41 from below while the slug 54 and associated slugs 61 and 63 are making impressions so that the operating mechanism is relieved from excess strains during the 60 actual printing operations. If for any reason it should become necessary to temporarily adjust the pressure developed by the stamping or pressure member 17 in opposition to the printing pressure developed by the printing slugs, this 65 adjustment may be accomplished at will by

swinging the operating lever 36 on its pivot 37 to rotatably adjust the shaft 33 and eccentrics 34 carried thereby and to thus temporarily change the location of the pivot 26 on which the lever 25 is arranged to swing. When the printing slug 54, and associate slugs 61 and 63 have made their impressions on the paper or equivalent material located on the bed plate 12, the pin 76 will engage the tripping pawl 74 which accordingly will be swung on its pivot 73 in a direction to develop 10 a pull upon the link 69 and swing the arm 65 toward the left in Fig. 2 and to thereby remove its shoulder 67 from beneath the lower carrier 41. Continued operation of the mechanism will rock the levers 25 and 44 in inverse relation in return 15 directions so that the upper carrier 16 will be moved upwardly while the lower carrier 41 at the same time will be moved downwardly back to the positions shown in Fig. 2, whereupon the cycle of operations described will be repeated. As the 20 shaft 53 is rotated during the operations set forth above, the crank member 156 will rotate therewith and by means of the link 151 and related elements will reciprocate the pushing member 145 at periodic intervals in a manner to advance the 25 slugs 54 accumulated in the trough 144 in successive steps lengthwise thereof; the operative movements of the pushing member 145 to shift the accumulated slugs 54 in the trough 144 are so timed that the end portion of the trough 144 30 located in registry with the chute 143 will always be free to receive the slugs 54 as they are successively transferred from the lower carrier 41.

In proper synchronism with the operative steps above set forth, the upper run of the chain 110 35 is actuated by the pawl 122 and ratchet wheel 121 and their associated elements to shift the advancing member 102^a lengthwise of the chute 78 to thereby bring the forward terminal slug 54 therein into position for transfer to the lower 40 carrier 41 at the proper time. It will be noted that the force developed by the advancing member 102^a is exerted centrally of the supply of slugs 54 in the chute 78; it will further be noted that the slide block 106 in co-operation with the centrally located lug 120 and centrally located upper run of the chain 110, prevents the force of the advancing member 102^a from being exerted in an unbalanced manner on the slugs 54 and thereby assures a free advance of the latter without any 45 tendency to bind in said chute 78.

It will be understood while the operations described in detail hereinbefore are taking place, that the other parts of the apparatus are being operated in proper synchronism therewith; in other words, the distributing roll 175 is being rotated in the reservoir 176, the platen 194 is being 55 rotatably actuated on its axis 195, and the lever 158 with its pin 162 is being periodically rocked to separate the terminal slug 54 if it should have 60 temporarily adhered to an adjacent slug.

The machine is extremely simple in construction and operation, and provides for the addition of predetermined items to previously printed material in such a manner as to personalize the 65 printed matter and to give the impression that all of it was specially printed for instance for a particular person or a particular purpose. The apparatus further provides for the combination of certain fixed additional items to be printed 70 in associated relation with the successive changing items. The apparatus in addition is constructed to automatically prevent injury to the mechanism as a result of the development of unexpected obstructions in the operation there- 75

of, and accordingly requires no particularly skilled supervision in its operation. All that is required on the part of the operator is the placing of a supply of slugs 54 in the chute 78; if the associated items are to be printed in predetermined relation to the changeable items contained on the slugs 54, the proper slugs 61 and 63 or their equivalent need only be placed in proper position on the lower carrier 41. In the operation of the apparatus, the slugs 54 which print the successively different items and add the same to the previously printed matter, are transferred bodily to the lower carrier 41 for movement therewith to the printing position in opposition and in operative synchronism with the pressure member 17; with this arrangement, absolutely uniform impressions are produced in a simple and efficient manner. It will be obvious that with the instant apparatus additional matter composed either wholly or in part of successively changing items, may be added to matter previously produced by any suitable printing operation such as printing from type or lithographing, etc. In any case, when the additional item or items have been added to the previously produced material, the result will present the appearance of having been produced coincidentally in a manner to give the printed matter as a whole a highly personalized character, giving the impression of having been produced specially, for instance, for the recipient.

Various changes in the specific forms shown and described may be made within the scope of the claims without departing from the spirit of the invention.

35 I claim:

1. In a printing machine of the kind described, a support for a plurality of slugs provided with type items to be printed, printing mechanism including a printing member normally in receiving relation to said support, a transfer device for transferring successive slugs from said support to said printing member, mechanism for operating said device, and a connection between said mechanism and device adapted to be automatically broken upon the development of abnormal resistance to the operation of said transfer device.

2. In a printing machine of the kind described, a support for a plurality of slugs provided with type items to be printed, printing mechanism including a printing member normally in receiving relation to said support, a transfer device for transferring successive slugs from said support to said printing member, mechanism including an operating member for operating said device, and a detent connecting said lever with said device adapted to yield and automatically break said connection upon the development of abnormal resistance to the operation of said transfer device.

3. In a printing machine of the kind described, a chute for a plurality of slugs provided with type items to be printed, printing mechanism including a printing member normally in receiving relation to said chute, a guide wall extending across the delivery end of said chute, a transfer device slideable along said wall for transferring successive slugs from said chute to said printing member, mechanism including a rocking lever for reciprocating said transfer device on said guide wall, and a detent yieldingly mounted on said lever for connecting the latter with said transfer device, said detent being automatically shifted to break said connection upon the development of abnormal resistance to the operation of said transfer device.

4. In a printing machine of the kind described, a horizontal chute for a plurality of slugs provided with type items to be printed, an upright wall extending lengthwise of said chute, a transverse extension at one end of said wall, an upright 5 guide wall extending transversely across the delivery end of said chute in spaced relation to said transverse extension to form therewith an exit passage, said guide wall being provided with a longitudinal slot, printing mechanism including 10 a vertically operating printing member normally in receiving relation to said exit passage, a block slidably mounted in the slot of said guide wall, a transfer device carried by said block and movable therewith along said guide wall for transferring 15 successive slugs from said chute through said exit passage to said printing member, a guide rod extending in parallel relation to said guide wall, an arm slidably mounted on said rod and connected with said block, a projection movable 20 with said arm, a rocking lever pivotally movable in a horizontal plane, means for operating said lever, and a detent yieldingly mounted on said lever and normally in engagement with said projection to operatively connect said lever with 25 said transfer device, said detent being automatically disconnected from said projection to break the connection between the rocking lever and the transfer device upon the development of abnormal resistance to the operation of the latter. 30

5. In a printing machine of the kind described, printing mechanism including a printing member, a support for a plurality of slugs provided with type items to be printed, means for transferring successive slugs from said support to 35 said printing member, an intermittently operated endless device having its one run in operative relation to said support, and means detachably connected with said one run of said operating device and movable thereby relatively to said support for intermittently shifting said slugs to bring successive slugs into operative relation to said transferring means.

6. In a printing machine of the kind described, printing mechanism including a printing member, a chute for a plurality of slugs provided with type items to be printed and having a slot extending lengthwise thereof, means for transferring successive slugs from said chute to said printing member, an endless chain having its 45 one run movable in said slot, means for operating said chain in intermittent steps to correspondingly move said one run thereof lengthwise of said slot, and advancing means detachably connected with said one run of said chain and 50 intermittently movable thereby lengthwise of said chute to bring successive slugs into operative relation to said transferring means.

7. In a printing machine of the kind described, printing mechanism including a printing member, a chute for a plurality of slugs provided with type items to be printed and having a slot extending lengthwise thereof, means for transferring successive slugs from said chute to said printing member, an endless chain having its 60 one run movable in said slot, means for operating said chain in intermittent steps to correspondingly move said one run thereof lengthwise of said slot, an advancing member detachably connected with said run of said chain and 65 intermittently movable thereby lengthwise of said chute to bring successive slugs into operative relation to said transferring means, and means carrying said advancing member and movable therewith by said chain, said means being op- 70

75

- erative to connect said advancing member with said chain and to disconnect it therefrom at will.
8. In a printing machine of the kind described, printing mechanism including a printing member, a chute for a plurality of slugs provided with type items to be printed and having a slot extending lengthwise thereof, means for transferring successive slugs from said chute to said printing member, an endless chain having its one run movable in said slot, means for operating said chain in intermittent steps to correspondingly move said one run thereof lengthwise of said slot, an advancing member detachably connected with said run of said chain and intermittently movable thereby lengthwise of said chute to bring successive slugs into operative relation to said transferring means, a carrier for said advancing member, and a slide block movable lengthwise of said chute in spaced parallel relation to said chain for guiding said carrier and for acting as a fulcrum on which the latter may be pivotally operated to selectively connect and disconnect the advancing member with and from said chain.
- 25 9. In a printing machine of the kind described, printing mechanism including a printing member, a chute for a plurality of slugs provided with type items to be printed and having a slot extending lengthwise along the longitudinal centre of said chute, a grooved wall extending lengthwise of said chute in spaced parallel relation to the slot thereof, means for transferring successive slugs from said chute to said printing member, an endless chain having its one run movable in said slot, means for intermittently operating said chain to correspondingly move said one run lengthwise of said slot, an advancing member detachably connected with said run of said chain and intermittently movable thereby lengthwise of said chute to bring successive slugs into operative relation to said transferring means, a lever carrying said advancing member and extending transversely across said grooved wall, and a slide block movable lengthwise of said grooved wall and connected with said lever for guiding the latter and said advancing member lengthwise of said chute, said slide block selectively serving as a fulcrum for said lever whereby the latter may be pivotally operated to connect and disconnect the advancing member with and from said chain at will.
10. In a printing machine of the kind described, printing mechanism including a printing member, a chute for a plurality of slugs provided with type items to be printed and having a slot extending lengthwise along the longitudinal centre of said chute, a wall extending lengthwise of said chute and provided with a longitudinal undercut groove means for transferring successive slugs from said chute to said printing member, an endless chain having its one run movable in said slot, means for intermittently operating said chain to correspondingly move said one run lengthwise of said slot, an advancing member detachably connected with said run of said chain and intermittently movable thereby lengthwise of said chute to bring successive slugs into operative relation to said transferring means, a lever carrying said advancing member and extending transversely across said grooved wall, a slide block movable lengthwise of said undercut groove and connected with said lever for guiding the latter and said advancing member lengthwise of said chute, and a rib extending 75 along the inner edge of said block in said groove

for maintaining said block therein and for selectively serving as a fulcrum on which said lever may be pivotally operated to connect and disconnect the advancing member with and from said chain at will.

11. In a printing machine of the kind described, a support for a plurality of slugs provided with variable type items to be printed, printing mechanism including a movable printing member normally located in receiving relation to said support, means operating in timed relation to said printing member for shifting successive slugs from said support to a printing position on said printing member, clamping means for removably clamping said slugs in place on said printing member, and means on said clamping means for accommodating additional type items in associated printing relation to the type item on each slug successively carried by said printing member.

12. In a printing machine of the kind described, a support for a plurality of slugs provided with variable type items to be printed, printing mechanism including a movable printing member normally located in receiving relation to said support, means operating in timed relation to said printing member for shifting successive slugs from said support to a printing position on said printing member, means on said printing member for carrying additional type items in associated printing relation to the type items on each slug successively carried by said printing member, and clamping means for removably clamping successive slugs in place on said printing member.

13. In a printing machine of the kind described, a support for a plurality of slugs provided with variable type items to be printed, printing mechanism including a movable printing member normally located in receiving relation to said support, means operating in timed relation to said printing member for shifting successive slugs from said support to a printing position on said printing member, means on said printing member for carrying additional type items in associated printing relation to the type items on each slug successively carried by said printing member, clamping means for removably clamping successive slugs in place on said printing member, and means on said clamping means for carrying additional type items in associated printing relation to said first named additional type items and to the type item on each slug successively carried by said printing member.

14. In a printing machine of the kind described, a support for a plurality of slugs provided with type items to be printed, printing mechanism including a printing member normally in receiving relation to said support, a transfer device for transferring successive slugs from said support to said printing member, mechanism for operating said device, and means for automatically impacting successive terminal slugs on said support to disrupt any developed clinging to an adjacent slug prior to the transferring operation of said transfer device.

15. In a printing machine of the kind described, a support for a plurality of slugs provided with type items to be printed, printing mechanism including a printing member normally in receiving relation to said support, a transfer device for transferring successive slugs from said support to said printing member, mechanism for operating said device, pivotally mounted impacting means, and means for periodically actuating said impacting means to loosen a terminal slug which may cling to an adjacent slug,

prior to the transferring operation of said transfer device.

16. In a printing machine of the kind described, a support for a plurality of slugs provided with type items to be printed, printing mechanism including a vertically reciprocable printing member normally in receiving relation to said support, means for transferring successive slugs from said support to said printing member, a releasable device for supporting said printing member to resist the impression pressure during printing, a pivotally mounted impacting device, an adjustable projection carried by said impacting device, a bracket movable with said releasable device, and means for shifting the latter to and from its operative position to coincidentally cause said bracket to operate said impacting device and thereby loosen a terminal slug which may cling to an adjacent slug, prior to the transferring operation of said transferring means.

17. In a printing machine of the kind described, printing mechanism including a printing member arranged to carry type items to be printed, inking means for inking successive type items on said printing member prior to the printing operation, means including a distributing roll for supplying said inking means with ink, and adjustable mechanism for intermittently rotating said distributing roll to a varying extent.

18. In a printing machine of the kind described, printing mechanism including a printing member arranged to carry type items to be printed, inking means including inking rollers,

for inking successive type items on said printing member prior to the printing operation, a rotatably mounted inking platen over which said inking rolls are adapted to travel, and means for intermittently rotating said inking platen.

19. In a printing machine of the kind described, printing mechanism including a vertically reciprocable printing member arranged to carry type items to be printed, inking means, including inking rollers, for inking successive type items on said printing member prior to the printing operation, a rotatably mounted inking platen over which said inking rollers are adapted to travel, means for rotatably actuating said platen, and means for vertically operating said printing member and for coincidentally operating said platen actuating means to intermittently rotate said platen.

20. In a printing machine of the kind described, a support for a plurality of slugs provided with type items to be printed, printing mechanism including a printing member normally in receiving relation to said support, means for transferring successive slugs from said support to said printing member to coincidentally remove successive preceding slugs therefrom, a chute for receiving the discarded slugs, a trough for receiving the slugs discarded from said chute, a pushing member, and adjustable means for reciprocating said pushing member relatively to said trough whereby the discarded slugs are intermittently shifted lengthwise thereof.
